FLOOR POLISHING ATTACHMENT FOR VACUUM CLEANERS

Edward P. Russell, El Segundo, Calif., assignor
to Interstate Engineering Corporation, El
Segundo, Calif., a corporation of California

Application March 6, 1953, Serial No. 23,928

Term of patent 7 years

(Cl. D9—2)

To all whom it may concern:

Be it known that I, Edward P. Russell, a citizen
of the United States, residing at El Segundo, in
the county of Los Angeles, State of California,
have invented a new, original, and ornamental
Design for a Floor Polishing Attachment for
Vacuum Cleaners, of which the following is a
specification, reference being had to the accom-
panying drawing, forming a part hereof.

Fig. 1 is a perspective view of a floor polishing
attachment for vacuum cleaners, embodying my
new design;

Fig. 2 is a top plan view of the same;

Fig. 3 is a rear view in elevation of the same;
and

Fig. 4 is a side view in elevation of the same.

I claim:

The ornamental design for a floor polishing
attachment for vacuum cleaners, as shown.

EDWARD P. RUSSELL.
